E. F. MINER

PULLER FOR PRIMARY CUTOUT PLUGS

Filed June 2, 1925

Inventor:
Ellsworth F. Miner,
by *Alvord & Lunt*,
His Attorney.

Patented Mar. 30, 1926.

UNITED STATES PATENT OFFICE.

ELLSWORTH F. MINER, OF LITCHFIELD, CONNECTICUT, ASSIGNOR TO GENERAL ELECTRIC COMPANY, A CORPORATION OF NEW YORK.

PULLER FOR PRIMARY CUT-OUT PLUGS.

Application filed June 2, 1925. Serial No. 34,460.

To all whom it may concern:

Be it known that I, ELLSWORTH F. MINER, a citizen of the United States, residing at Litchfield, in the county of Litchfield and State of Connecticut, have invented certain new and useful Improvements in Pullers for Primary Cut-Out Plugs, of which the following is a specification.

The present invention relates to safety devices for operating high potential electrical apparatus, and more especially to pullers for removing and replacing the plugs of primary cutouts.

The object of my invention is the provision of an improved plug puller which may be positively connected to the plug of a primary cutout with facility, which shall be strong and durable and composed of few and simple parts and which shall be of low manufacturing cost.

Primary cutouts are fused safety devices employed on the high potential side of distribution transformers for lighting circuits usually mounted on poles out of doors and exposed to the weather. The supply potentials range from twenty-three hundred to seventy-five hundred volts, and accordingly there is more or less danger to human life in the interruption of the circuit by pulling out of a plug, especially during rainy weather.

In order that the lineman may remain at a safe distance from the cutout when it becomes necessary to remove the plug, it is common practice to provide plug pullers which consist of a relatively long pole of insulation having means at one end for coupling it to the plug. The plugs sometimes offer considerable resistance to being removed, and when removed they require to be held from falling to the ground, since they are usually made of porcelain and are easily broken by impact.

One embodiment of the invention is shown in the accompanying drawing, in which Fig. 1 is a side elevation of an improved plug puller with the parts in the relative positions for application to the knob of a plug; Fig. 2 is a similar view with the parts in their relative engaged positions, and Fig. 3 is an elevation at right angles to the elevations of Figs. 1 and 2.

The pole 1 is a plain cylindrical wooden rod usually three to four feet in length and

provided at one end with the plug engaging and holding means.

The plug engaging and holding means comprises a hooked member 2 and a holding or retaining member 3. The hooked member 2 is a sheet metal cylinder with its lower end fitted like a ferrule upon the pole 1 and secured against displacement by a transverse rivet or pin 4, while its upper end has a slot like an inverted T cut therein to provide a side opening 5 for the reception of the knob 6 of the plug and two transversely extending horns 7 adapted to receive between them the neck of the plug knob 6 and to engage at their lower edges with the upper surface of the knob. The means 3 for holding and retaining the knob 6 in position between the engaging horns 7 consists of a triangular guard plate provided at its lower end with a sleeve 8 freely swiveled upon the lower portion of the hooked member 2 and having a 180° slot 9 therein adapted to receive one end of the rivet or pin 4 which serves to prevent longitudinal displacement thereof and to limit its swiveling movement.

To connect my puller to a plug, the guard plate 3 is rotated to stand away from the T slot in the hooked member 2 so that the latter may receive the knob 6 therein, as indicated in Fig. 1. As the hooked member 2 moves into engaging relation, the guard plate 3 comes into contact with the edge of the elongated flange 10 of the plug so that it is prevented from turning with the hooked member 2 as the latter is rotated by the lineman into the holding position indicated in Fig. 2 in which the guard plate 3 stands opposite the T slot and serves to prevent the displacement of the knob 6 from the horns 7 until the plug has been returned to operating position and the guard plate displaced by a swiveling movement of the hooked member to the original position, as shown in Fig. 1.

While I have shown and described the best embodiment of the invention known to me, I do not desire to be restricted thereto.

What I claim as new and desire to secure by Letters Patent of the United States, is:—

1. A plug puller comprising a hooked member having provision for receiving the end of a plug sidewise therein, and a guard member swiveled relatively to the hooked

- 2
- member and adapted in one position to receive the end of a plug in engagement with said hooked member.
5. 2. A plug puller comprising a hooked member provided with two spaced horns adapted to receive between them the end of a plug, and a guard member swiveled relatively to said hooked member and adapted upon rotation of said hooked member relative to the plug to be positioned opposite the space between said horns to retain the plug in engagement therewith and to be moved into inoperative position.
- 10 10. 3. A plug puller comprising a hooked member provided with two spaced transverse horns adapted to receive between them the end of a plug, and a guard member mounted for limited swiveling movement relative to said hooked member and adapted
- 15 15. 4. A plug puller comprising a tubular member having two spaced transverse horns and a guard member having a plate supported by a sleeve swiveled upon said tubular member and adapted in one position to close the space between said horns and in another position to free said space.
- 20 5. A plug puller comprising a tubular member having a T-shaped recess, a guard member having a triangular plate supported by a sleeve swiveled upon said tubular member, and means for limiting the swiveling movement of said guard member.

In witness whereof, I have hereto set my hand this 28th day of May, 1925.

ELLSWORTH F. MINER.
